FOUR-STROKE CYCLE INTERNAL COMBUSTION ENGINE OF THE SLEEVE VALVE TYPE

Ernest Schmid, Annecy, France; vested in the Alien Property Custodian

Application November 28, 1939, Serial No. 306,558
In Germany January 31, 1939

2 Claims. (Cl. 123—75)

In the four-stroke cycle internal combustion engines of the sleeve valve type the construction of the sleeve valve or valves and of the valve gears has been a problem for the constructors.

In the particular case in which it is intended to realise a light engine and to obtain high speeds the two concentric sleeve valve systems are useless, so that it becomes necessary to use a system with a single sleeve as light as possible, consequently very thin. A sleeve of this type would present besides its lightness and its low resistance to heat exchange the advantage to permit to obtain an unequalled self-tightness, for example in making a slit over its entire length, in order to obtain an open sleeve.

This proposition was however never made until now for the reason that such an open sleeve would immediately be distorted in such a manner that it would become useless. In fact it is known that all the control mechanisms of sleeve valves submit the sleeve to asymmetric distorting efforts, which could not be endured by a sleeve built in the above mentioned manner.

In order to bring a new solution in the structure of motors light and rapid of the sleeve valve type, the present invention provides a combination of a certain type of sleeve valve with a certain type of gear mechanism, both unknown until now.

The sleeve is to be thin, slit over its entire length along a straight line or along a curved line of any shape. In any case the slit can be established without right angles zigzags, given the fact, that a thin sleeve of which the thickness of the wall can be for example $\frac{1}{10}$ of the bore, shows practically no sensible loss even with the highest pressures.

With this single sleeve valve reciprocating between cylinder and piston and moved by a disposition known as two-eccentric gear system, i. e., comprising two eccentrics of which one works at the speed of the crankshaft and the other at half that speed, and permitting to control the sleeve always positively with an irregular movement showing quite noticeable dead positions at the neighbourhood of the highest pressures, a carrying mechanism is combined, established in such a way that in all the positions of the sleeve the result of the impulse coincides with the axis of the cylinder.

The combination according to this invention constitutes an enormous progress compared to the previous dispositions, the light and rapid engines which can be built in this manner being particularly useful for aviation.

The appended drawings show an embodiment of a four-stroke cycle internal combustion engine according to the present invention.

Fig. 1 shows an axial section of the cylinder taken perpendicularly to the crankshaft and to the shafts of the eccentrics controlling the sleeve.

Fig. 2 shows the gearing mechanism in perspective, seen from below.

Fig. 3 is a cross section upon the line III—III of Fig. 1.

Fig. 4 shows a perspective view of the unmounted sleeve, of the two connecting members provided to move it, and of a coupling link part of the two-eccentric gear system.

15 In the cylinder 1 reciprocate the sleeve 2 and also the piston 3 of which the connecting rod 4 drives the crankshaft 5.

The sleeve is thin and slit over its entire length in 14. It controls the inlet ports and outlet ports 20 by means of the valve ports 15 and its upper edge.

25 On both sides and above the crankshaft are located the eccentrics 6 and 7 of the two-eccentric gear of which the coupling rods 8 and 9 move a rigid frame principally composed of two coupling links 10, of which only one is visible respectively seen in Figs. 1 and 4. Each of these coupling links supports a plug 11 engaging in one of the two coupling members 13 sliding in the slides located between the guides 12 extending the cylinder in the direction of the crankshaft. These coupling organs constitute sliding blocks.

30 The two sliding blocks are of such a shape that they partially surround the sleeve 2 without however entering into contact with its external cylindrical surface. This is shown clearly in Fig. 3. In this way the sleeve is only guided by the interior wall of the cylinder against which it lies closely and by the internal surface of the guides 12 made in order to extend the interior surface of the cylinder with which they have been simultaneously bored so as to have an unbroken continuity of surface.

35 Opposite the sliding blocks 13 symmetrically placed on both sides of the longitudinal axis of the sleeve and simultaneously moved in the axial direction by means of the two coupling links 10 and their plugs 11, the sleeve presents on the lower part projections 18 of rectangular cross section penetrating in grooves 19 of corresponding cross section of the sliding blocks 13. The thickness of these projections measured in radial direction is such that their external cylindrical surface is unable to enter into contact with the bottom of the grooves 19. This disposition, as 40 well as the radial display subsisting between slid-

ing blocks and sleeve is intended to avoid all transmission of a nonaxial effort from the sliding blocks to the sleeve, which they can only carry parallel to the axis once above and once below by means of the contact surfaces provided between the projections and the grooves and lying perpendicularly to the axis of the sleeve. The resultant of the forces moving the sleeve will always coincide with its axis, respectively with the axis of the cylinder.

The driving means constituted by the two coupling links 10 and the fastening screws 20 are, of course, absolutely rigid, and are moreover, moved by connecting rods 8 and 9 in such a manner that it will absolutely avoid every distorting action and ensure a symmetric movement of the sliding blocks 13.

It must also be remembered that the sleeve lies close against the inner surface of the guides 12 precisely where the wear of the cylinder takes place, i. e., there where the piston presses most. These guides extend the cylinder in an absolutely rigid way, Figs. 1 and 3 showing clearly the disposition of the supporting ribs 12' intended to strengthen them.

Also Fig. 1 does show the cylinder head without piston rings in regard of the sleeve, it is evident that for certain engines it would be of interest to have such piston rings.

What I claim is:

1. In a sleeve-valve type internal combustion engine, a cylinder, a piston and a single sleeve-valve made of material as thin as possible, between the said cylinder and the piston, a slit extending without baffling over the entire length of the sleeve-valve, symmetrically disposed driving means for reciprocating the sleeve-valve, rigid bearings independent of the sleeve-valve, taking up every stress of the driving means not directed parallelly to the cylinder axis and connection means between the sleeve-valve and the driving means, the said connection means being so directed that they remain disconnected for every effort non-parallel to the said cylinder axis.

2. In a sleeve-valve type internal combustion engine, a cylinder, a piston and a single sleeve-valve made of one piece of material as thin as possible between the said cylinder and piston, a slit extending without baffling, from end to end of the sleeve-valve, two diametrically opposed driving means reciprocating the sleeve-valve, rigid guides for said driving means, extending axially and integral with the engine casing, means for synchronously reciprocating the said driving means, and a bracket shaped connection extending in transversal planes between the sleeve and both driving means.

ERNEST SCHMID.
